No. 12,403

Aug. 9, 1881

UNITED STATES PATENT OFFICE.

LE ROY W. FAIRCHILD, OF NEW YORK, N. Y.

DESIGN FOR A PENCIL-CASE.

SPECIFICATION forming part of Design No. 12,403, dated August 9, 1881.

Application filed April 5, 1881. Term of patent 7 years.

To all whom it may concern:

Be it known that I, LE ROY W. FAIRCHILD, a citizen of the United States, residing at New York, in the county and State of New York, 5 have invented a new and original Design for Cases for Pencils and similar articles, of which the following is a specification, reference being had to the accompanying illustration, forming part thereof.

10 The accompanying print represents a side elevation, and also an end view, of my design.

The design consists of a case the body of 15 which represents a bottle, as shown at A, in the bottom of which is inserted a small compass, as shown in the end view at E. The neck of the bottle may be ornamented or not, as preferred, and has a ring, D, attached, by which to suspend the case.

20 B represents the extension portion of the case, and is provided at its outer end with a part, C, made to represent the head of a bottle with a cork secured by wire, after the style of champagne-bottles, as shown, the parts be-

ing so arranged that when the case is closed it has the appearance of a bottle with a compass inserted in its lower end.

The several parts may be made of different metals or different shades of the same metal, and thus be made to present a very rich appearance. It is designed to be worn on a watch-chain as a charm or ornament, but may be utilized as a case for a magic pencil, tooth-pick, glove-buttoner, or any similar small implement.

Having thus described my invention, what 35 I claim is—

The herein-described design for a case, consisting of the bottle A, having the compass E placed in the bottom thereof, and the neck of the bottle having a ring, D, attached, substantially as described.

LE ROY W. FAIRCHILD.
